CLAIM

U.S. PATENT DOCUMENTS

The ornamental design for screw, as shown and described.

DESCRIPTION

FIG. 1 is a first perspective view of the screw embodying the new design;

FIG. 2 is a second perspective view thereof;

FIG. 3 is a left side view thereof;

FIG. 4 is a right side view thereof;

FIG. 5 is a point end view thereof; and,

FIG. 6 is a head end view thereof.

FIGS. 1-6 show features of a screw in broken lines. These features do not form any part of the claimed design. The broken lines immediately adjacent the solid-line portions of the design form the boundary of the design, with the broken lines forming no part of the claimed design.
